DISPLAY TABLE OR THE LIKE

Morris Rand, Boston, Mass., assignor to Rand Associates, Inc., South Boston, Mass., a corporation of Massachusetts

Filed May 10, 1963, Ser. No. 74,836

Term of patent 14 years

(Cl. D80—2)

FIG.1

FIG.3

FIG. 1 is a front perspective view of a display table showing my new design, the rear being essentially the same as the front shown;

FIG. 2 is a fragmentary top plan view thereof; and

FIG. 3 is an elevational view taken from one end thereof, the opposite end being substantially the same as the end shown.

The characteristic feature of the design resides in the curved inset side panels of the table as shown.

I claim:

The ornamental design for a display table or the like, substantially as shown and described.
